AIR NOZZLE AND IONIZING UNIT FOR
ELECTROSTATIC AIR FILTERSGeorge F. Landgraf, Pittsburgh, Pa., assignor to
Trion, Inc., McKees Rocks, Pa., a corporation
of Pennsylvania

Application January 13, 1950, Serial No. 138,355

7 Claims. (Cl. 183—7)

1

This application relates to an air nozzle and ionizing unit for electrostatic air filters, particularly air filters of the type having an ionizing unit and a collecting unit which are separately mounted in a housing and which may be separately removed for purposes of maintenance and repair. The air nozzle and ionizing unit which I have invented combines in one structure a specially designed air nozzle and an ionizing unit which can readily be installed and removed from the front of the housing as a single structure. The air nozzle is designed to prevent "blow-by" and at the same time it provides a support for the ionizing tubes of the ionizing unit. It also carries supports for the ionizing wires which are spaced between the tubes.

In the accompanying drawings I have illustrated a present preferred embodiment of my invention, in which—

Figure 1 is a plan view of my unit;

Figure 2 is a rear elevation view;

Figure 3 is a front elevation view;

Figure 4 is a section along the lines IV—IV of Figure 2;

Figure 5 is an end view;

Figure 6 is a fragmentary plan view similar to Figure 1 but on an enlarged scale;

Figure 7 is a section along the lines VII—VII of Figure 4 but on an enlarged scale; and

Figure 8 is a vertical section through one of the ionizing tubes along the lines VIII—VIII of Figure 7.

An electrostatic air filter of the type for which my invention is intended has an ionizing unit which charges solid particles carried by the air as it first enters the filter and a collecting unit which removes the charged solid particles from the air before the air leaves the filter. The ionizing unit comprises a row of tubes spaced parallel to each other across the front of the filter and a series of ionizing wires extending between and parallel to the tubes. A large potential difference is maintained between the wires and the tubes. The collecting unit comprises a series of plates spaced parallel to each other across the housing of the filter so that all air which enters the filter passes between the plates after it leaves the ionizing unit. A high potential difference is maintained between alternate plates, and the charged particles in the air are attracted to and remain on the plates from which they are washed at intervals. As stated above I have invented an air nozzle and ionizing unit which can be assembled in the front of the filter and removed from the unit as a single unit. This obviously facilitates maintenance and repair.

2

Figure 3 shows the front of my unit which comprises a rectangular frame 9, ionizing tubes 10, and ionizing wires 11. As shown in Figures 1 and 2 flanges 12 and 13 extend from the top and bottom inner edges of the frame in the direction of air flow through the unit and also slope inwardly to slightly restrict the air passage, that is, the flange 12 slopes slightly downwardly and the flange 13 slopes slightly upwardly. Flanges 14 and 15 extend in the direction of the air flow from the inner side edges of the frame and (as shown in Figures 1 and 6) also slope inwardly to slightly restrict the air flow. At a point approximately in line with the ionizing tubes 10, the flanges 14 and 15 are curved outwardly and in effect form two additional ionizing tubes. From Figures 1 and 2 it will be noted that all of the air which enters through the frame 9 passes between tubes and wires or between the curved side flanges 14 and 15 and the wires. This avoids all "blow-by." In other words, all of the particles in the air passing through the filter are subjected to the high electrostatic field maintained between the wires and the tubes. If desired a "hum suppressor" 16 such as described in my copending application Serial No. 72,885 filed January 26, 1949, can be added to my unit to prevent "howling" of the ionizing wires in dry weather.

Figures 2, 4 and 5 show the structure for supporting the ionizing wires 11. The frame 9 carries two insulators 17 above the top flange 12 and spaced adjacent each end of the flange and two insulators 18 below the flange 13 and spaced adjacent each end of the flange. The insulators 17 support a top bar 19 which is in the form of an angle bolted to the insulators and the insulators 18 support a bottom bar 20 which is also in the form of an angle bolted to the insulators. The bars 19 and 20 have a series of holes spaced along their length. S hooks 21 are placed in the openings in the top bar 19 and a loop is formed in each ionizing wire and passed over an S hook. Small springs 22 are hooked at one end into the openings in the bottom bar 20 and the bottom of each ionizing wire is looped to engage the other end of one of these springs, the springs thus serving to hold the wires taut.

Figures 6, 7 and 8 show the structure for supporting the ionizing tubes 10. The flanges 12 and 13 are scalloped to provide clearance for the ionizing wires. The widest portions 23 of the flanges terminate in tongues 24 which extend into slots cut in the tubes 10 and are bent over as shown in Figure 8 to lock the tubes in position.

From the foregoing it appears that my air nozzle and ionizing unit is relatively simple to construct because few assembly operations are involved. The air nozzle prevents "blow-by." It also supports the ionizing tubes and wires so that the entire unit can be installed as a unitary structure in an air filter and easily removed for maintenance and repair.

While I have described a present preferred embodiment of my invention, it is to be understood that it may be otherwise embodied within the scope of the following claims.

I claim:

1. An air nozzle for electrostatic air filters having an ionizing unit having two sets of electrodes, one set being charged oppositely to the other set comprising a rectangular frame having a rectangular opening therein, and flanges extending in the direction of air flow from the edges of the frame forming said opening, two flanges on opposed sides having means for supporting between them one set of electrodes of the ionizing unit, the two other sides sloping inwardly from the front of the frame and then curving outwardly at a point substantially in line with the electrodes carried by the first said flanges.

2. An air nozzle for electrostatic air filters having an ionizing unit having two sets of oppositely charged electrodes, one set comprising tubes, the other set comprising wires, said nozzle comprising a rectangular frame having a rectangular opening therein, and flanges extending in the direction of air flow from the edges of the frame forming said opening, two flanges on opposed sides having tongues adapted to extend into slots in tubes of the ionizing unit and thereby support the tubes, the two other sides sloping inwardly from the front of the frame and then curving outwardly at a point substantially in line with the tubes.

3. An air nozzle for electrostatic air filters having an ionizing unit having two sets of oppositely charged electrodes, one set comprising tubes, the other set comprising wires, said nozzle comprising a rectangular frame having a rectangular opening therein, and flanges extending in the direction of air flow from the edges of the frame forming said opening, two flanges on opposed sides being scalloped to provide clearance for ionizing wires of the ionizing unit, the portions of said flanges furthest from the frame terminating in tongues adapted to extend into slots in tubes of the ionizing unit and thereby support the tubes, the two other sides sloping inwardly from the front of the frame and then curving outwardly at a point substantially in line with the tubes.

4. An air nozzle and ionizing unit for electrostatic air filters comprising a rectangular frame

having a rectangular opening therein, flanges extending in the direction of air flow from the edges of the frame forming said opening, two opposed flanges having means for supporting tubular electrodes of the ionizing unit, a bar mounted on the rear side of the frame adjacent each flange which supports the tubular electrodes but electrically insulated therefrom, and wire electrodes supported by the bars extending between the ionizing tubes and side flanges and parallel thereto.

5. An air nozzle and ionizing unit for electrostatic air filters comprising a rectangular frame having a rectangular opening therein, flanges extending in the direction of air flow from the edges of the frame forming said opening, ionizing tubes supported by said flanges, ionizing wires extending between and parallel to the tubes and side flanges, and supports for said wires mounted on the rear sides of said frame but electrically insulated therefrom.

6. An air nozzle and ionizing unit for electrostatic air filters comprising a rectangular frame having a rectangular opening therein, flanges extending in the direction of air flow from the edges of the frame forming said opening, ionizing tubes extending across the frame and parallel to each other, said tubes having slots adjacent each end, two flanges on opposed sides sloping inwardly and having tongues adapted to extend into said slots to support the tubes, ionizing wires extending between and parallel to the tubes, insulators mounted on the rear face of the frame adjacent to but spaced from the flanges which support the tubes, and bars mounted on the insulators and supporting the ionizing wires.

7. An air nozzle for electrostatic air filters having an ionizing unit one set of electrodes of which are tubes, said nozzle comprising a rectangular frame having a rectangular opening therein, and flanges extending in the direction of air flow from the edges of the frame forming said opening and sloping inwardly, two flanges on opposed sides having means for supporting between them tubes of the ionizing unit, the two other sides sloping inwardly from the front of the frame and then curving outwardly at a point substantially in line with the tubes.
